Inventor:

James W. Kennedy,

By Mrs. E. Valdo, Atty.

UNITED STATES PATENT OFFICE.

JAMES W. KENNEDY, OF CHICAGO, ILLINOIS, ASSIGNOR, BY MESNE ASSIGNMENTS, TO THE KENNEDY TYPEWRITER COMPANY OF MANHATTAN, OF NEW YORK, N. Y., A CORPORATION OF NEW YORK.

LINE-SPACING MECHANISM FOR TYPE-WRITING MACHINES.

No. 829,137.

Specification of Letters Patent.

Patented July 27, 1909.

Original application filed April 2, 1904, Serial No. 201,284. Divided and this application filed May 31, 1904, Serial No. 310,484. Renewed October 5, 1908. Serial No. 456,220.

To all whom it may concern:

Be it known that I, JAMES W. KENNEDY, a subject of the King of Great Britain, residing at Chicago, Cook county, Illinois, have invented certain new and useful Improvements in Line-Spacing Mechanisms for Type-Writing Machines, of which the following is a complete specification.

This invention relates to typewriting machines, and relates particularly to linespacing mechanisms therefor.

This application is filed as a division of an application heretofore filed by me in the Patent Office on April 2, 1904, Serial Number 201,284, in which a line spacing mechanism for typewriting machines is shown but is not claimed.

A primary object of the invention is to provide a line spacing mechanism for typewriting machines of simple and durable construction, adapted to be operated by a pull on a lever applied to the platen carriage in a direction to retract said carriage.

In the accompanying drawings, illustrating my invention, Figure 1 is a partial front view of the platen of a typewriting machine equipped with a line spacing mechanism of my invention. Fig. 2 is a sectional elevation of a line spacing mechanism of my invention, 30 on the line 2—2 of Fig. 1. Fig. 3 is a sectional elevation thereof on the line 3—3 of Fig. 2. Fig. 4 is a side view of the parts shown in Fig. 3. Figs. 5 and 6 are enlarged detail views. And Fig. 7 is a view on the line 7—7 of Fig. 1.

Referring now to the drawings, 1 designates the platen frame and 2 the platen revolvably mounted therein, both of which may be of any usual or approved construction. Secured to the shaft of the platen 2 is a ratchet wheel 3, the teeth of which are adapted to be engaged by a spring pawl 4 pivoted on an arm 5 pivoted to the shaft of the platen 2 at the side of the ratchet wheel 3. Pivotal movement is adapted to be imparted to the arm 5 to advance and retract the pawl 4, in the following manner:

Revolvably mounted in suitable bearings in lugs 6 on the platen frame 1 is a rod or lever 7, secured in which is a lateral arm 8, the free end of which is connected to the arm 5 by means of a link 9.

In the preferable construction shown, see Fig. 5, the end of the arm 8 on the rod or

lever 7 is fitted to a suitable bearing in a block 10 pivotally mounted between lugs 11 formed at the end of the link 9, thus providing for angular movement of the arm 8 when the arm or lever 7 is rotated to operate the line spacing mechanism. A suitable hole or opening 12 is formed in the platen frame 1 through which the arm 8 extends, said opening 12 being made of such length as to provide for desired movement of said arm 8.

Coöperating with the actuating pawl 4, is a retaining pawl adapted to engage the teeth of the ratchet wheel 3 to prevent the platen 2 from being moved rearwardly when the actuating pawl 4 is retracted. As shown, said retaining pawl consists of a spring arm 13, which projects laterally from the platen frame 1 over said ratchet wheel, revolvably mounted in the end of which is a wheel or roller 14, which engages the teeth of said ratchet wheel. Any other desired or approved form of retaining pawl may, however, be used.

The feed of the line spacing mechanism and thus the distance between successive lines is controlled and regulated by means of a suitable adjustable stop, which limits the angular movement of the arm 8 on the lever 7. As shown, said stop consists of a plate 15 secured to a stub shaft 16 revolvably mounted in the platen frame. Formed on said plate 15 are a succession of steps or notches 17, 18 and 19, located at different distances from the axis of the stub shaft 16 and so disposed that by turning said plate 15 into proper positions any one of said surfaces may be brought into the path of travel of the arm 8, the relation being such that the step or notch 17 will permit a maximum movement of the arm 8, say the equivalent of a feed of three teeth of the ratchet wheel 3, the step or notch 19 a minimum movement of said lever arm, say the equivalent of one ratchet tooth, and the step 18 a movement of said lever arm intermediate the steps 17 and 19, say two ratchet teeth. The plate 15 is adapted to be turned into different positions to secure the different feeds by means of an arm 20 secured to the stub shaft 16 outside of the platen frame and to be secured in desired position by means of a pin 21 thereon adapted to engage holes 22 in said plate. To provide for engagement and disengagement of the pin 21 with the holes 22, the arm 20 is prefer-

ably a spring arm. In addition to operating the line spacing mechanism the rod or lever 7 is also used to retract the platen carriage. In the preferable construction shown, the forward end of said rod or lever 7 is bent downwardly below the bearings of said rod in the lugs 6 into close proximity to the keyboard of the machine in convenient position for manipulation by the operator. With this 10 construction, it is obvious that a pull on the rod 7 below the line of its bearing in a direction to retract said carriage will at the same time operate the line spacing mechanism.

The rod or lever 7 is maintained normally 15 at one limit of its pivotal movement by means of a suitable spring applied thereto. As shown, see Fig. 6, this is effected by means of a spring 23 one end of which is secured to a collar 24 and the other end to the 20 rear lug 6 in which the rod 7 is supported. To provide for adjusting the tension on said spring 23, the collar 24 is loose on said rod or lever and is adapted to be secured thereto in any desired angular adjustment by means of 25 a set screw 24^a. As shown, also said spring is inclosed in a recess formed in the collar 24. Contact of the arm 8 with the upper end of the slot 12 operates to limit the movement of the rod or lever 7 under the influence of 30 the spring 23.

The platen 2 is adapted to be turned manually to provide for inserting and adjusting the paper in the machine by means of knobs or finger grips 25 on the platen shaft, in a 35 familiar manner. In order that the actuating pawl 4 may not interfere with the rearward movement of the platen by means of the knobs or finger grips 25, means are provided to disengage said pawl from the teeth 40 of the ratchet wheel when said pawl is in retracted position. As shown, the means for this purpose consist of a pin 26 secured in the platen frame 1, which projects laterally into the path of travel of a cam surface 45 formed on a rearward extension 27 of the actuating pawl 4, the relation being such that when said pawl is fully retracted the cam surface on said rearward extension 27 will engage the pin 26 in such manner as to 50 move said pawl 4 pivotally to disengage the same from the ratchet teeth in the desired manner.

I claim as my invention—

1. In a line spacing mechanism for a type- 55 writing machine, the combination with the platen, a ratchet wheel secured to rotate therewith, a pivoted arm and an actuating pawl pivoted thereon, of means for imparting pivotal movement to said pawl carrying 60 arm, comprising a rotatable rod, an arm projecting laterally therefrom, a link which connects said arm with the pivoted pawl-carrying arm, the connection between said link and said arm on said rotatable rod consisting 65 of a block pivoted to said link and provided

with a bearing to which the arm on said rotatable rod is slidably fitted, substantially as described.

2. In a typewriting machine, the combination with a platen and its carriage, of a line 70 spacing mechanism comprising a rod extending transversely of the carriage and mounted to rock in bearings thereon, the forward end of this rod being extended forwardly and downwardly below its axis of rotation into 75 accessible proximity to the keyboard of the instrument, means connected to the rod whereby when it is rocked in its bearings the platen will be rotated, the relation being such that a pull on said rod in a direction to 80 retract the carriage will impart rotation to the rod in a direction to rotate the platen, said means consisting of a ratchet wheel on the platen shaft, a pivoted arm carrying a pawl in engagement with said ratchet wheel, 85 a device for tripping the pawl when said pawl-carrying arm is raised, a lateral arm carried by the aforesaid rod and extending laterally through a vertical slot in the carriage frame, means for regulating the up and 90 down movement of this arm in said slot, and a depending link pivotally connecting said arm to the pawl-carrying arm.

3. In a typewriting machine, the combination with the platen and its carriage, of a line 95 spacing mechanism comprising a transverse rod journaled in bearings on the carriage and having its forward end extending forwardly and downwardly to within proximity to the keyboard, whereby when the carriage is retracted by means of this downwardly turned 100 extremity the rod will at the same time be rocked in its bearings, means for transmitting this rocking movement to the platen consisting of a lateral arm attached to the rod, a link pivotally and slidably connected to said lateral arm, a pivoted arm below having pivotal connection with the lower end of said link and carrying a pawl, and means for tripping said pawl. 110

4. In a line spacing mechanism for a typewriting machine, the combination with the platen and its carriage, of a line spacing 115 mechanism comprising a ratchet wheel secured to rotate with said platen, a pivoted arm and an actuating pawl pivoted thereon, of means for imparting pivotal movement to said pawl carrying arm, comprising a rotatable rod, an arm projecting laterally therefrom, and a link which connects said arm 120 with the pivoted pawl carrying arm, said rotatable rod extending forward from the platen carriage and the end thereof being bent downwardly below its axis of rotation into accessible proximity to the keyboard of the instrument, the relation being such that a pull on said rod in a direction to retract the platen carriage will impart rotation thereto in a direction to operate the line spacing mechanism, substantially as described. 125 130

5. In combination with a typewriting machine embodying a sliding carriage carrying a rotatable platen and a ratchet wheel connected to the shaft of the platen, of a line spacing mechanism consisting of a rock shaft journaled in the carriage and provided with a forwardly extending operating arm or extension, a lateral arm carried by said rock shaft, this lateral arm working in a vertical slot in 10 an adjacent part of the carriage frame, a stepped adjustable plate on the carriage frame for varying the vertical throw of this arm, for the purpose set forth, a link pivotally depending from the end of said arm, another arm having one end pivoted coincident with the axis of the platen shaft and carrying a pawl on its free end, and means for tripping said pawl.
6. The combination with a typewriting machine embodying a sliding carriage carrying a rotatable platen and a ratchet wheel connected to the shaft of the platen, of a line
- spacing mechanism consisting of a rock shaft journaled in the carriage and provided with a forwardly extending operating arm or extension, a lateral arm carried by said rock shaft, a link depending from said arm, another arm pivoted coincident with the axis of the platen and carrying a pawl on its free end, said pawl having an upward extending cam-shaped tail piece extending above the pivot of the pawl, and a pin stationarily mounted on the carriage above the pawl and in line with the cam portion thereof, for the purpose herein set forth. 25 30 35
- In testimony, that I claim the foregoing as my invention, I affix my signature in presence of two subscribing witnesses, this 23rd day of May, A. D. 1904.
